UNITED STATES PATENT OFFICE.

MICHAEL J. N. SCHNEIDER, OF BLACK RIVER FALLS, WISCONSIN.

METALLIC ROOFING.

1,162,949.

Specification of Letters Patent.

Patented Dec. 7, 1915.

Application filed February 28, 1914. Serial No. 821,707.

To all whom it may concern:

Be it known that I, MICHAEL J. N. SCHNEIDER, a citizen of the United States, and a resident of Black River Falls, in the 5 county of Jackson and State of Wisconsin, have invented a new and useful Improvement in Metallic Roofing, of which the following is a specification.

This invention relates to an improvement 10 in metal roofing, and one of the principal objects thereof is to provide metal roofing strips which may easily and quickly be secured in coacting relation to form a roof, and which may be so arranged as to provide 15 a roof which is weatherproof and which presents a very neat and finished appearance.

Another object of the invention is to provide metal roofing strips as described, which 20 may be put in position without the necessity of employing skilled labor or special tools, and in a very short time.

A further object is to provide metal roofing strips of the class described, which may 25 be secured in a simple and strong manner in forming a roof, and which will be inexpensive to manufacture and will require a minimum amount of material, and will be highly efficient and durable.

30 A still further object of my invention is to provide anchor-pins for securing the roofing plates to battens, which pins are horizontally disposed with their length arranged transversely of the plates, whereby lifting 35 strain induced by winds or other climatic conditions upon said plates will be effectually resisted.

With these and other objects in view, which will become apparent as the description 40 proceeds, the invention resides in the construction, combination and arrangement of parts hereinafter more fully described and claimed, and illustrated in the accompanying drawing in which like characters of reference indicate like parts throughout the figures, of which—

Figure 1 represents a perspective view of a portion of the roof constructed according to my invention, Fig. 2 represents a detail, 50 transverse, sectional view taken on the plane indicated by the line 2—2 of Fig. 1; Fig. 3 represents a longitudinal, vertical, sectional view taken on the plane indicated by the line 3—3 of Fig. 1, and Fig. 4 represents a 55 transverse, sectional view showing the posi-

tion of the parts before the interlocking ribs are bent down.

Referring more particularly to the drawing, 5 indicates the rafters of a building, 6 the strips of sheathing arranged transversely of the rafters and in parallel and spaced relation with respect to each other, and 7 indicates the batten strips, which are laid upon the sheathing, transversely of the sheathing strips and in parallel relation with the rafters and positioned above said rafters, said batten strips, sheathing and rafters being secured by nails 8. The roofing strips are indicated at 9, and are all just exactly alike, said strips comprising a flat portion 10 of a width equal to the distance between any pair of the batten strips, said roofing strips at one edge being bent up at right angles as at 11 (Fig. 4), and then turned outwardly at its upper edge to form 70 a vertical, outer rib 12. The opposite edges of the strips are bent upwardly at right angles as at 13, a distance equal to the height of the batten strips, which are preferably square in cross-section, are then bent at 80 right angles as at 14 to the portion 13, and parallel with the flat portion 10, said portion 14 being of a width equal to the width of the batten strips, and at the outer edges of the portion 14, the strips are buckled 85 upon themselves to form inner ribs 15, whose outer folds 16 are parallel with portion 13 and are spaced from said portion a distance equal to the width of the batten strips. There is thus formed along one 90 edge of each strip what may be termed a hooked portion substantially rectangular in cross-section and of a cross-sectional area equal to the cross-sectional area of the batten strips, said hooked portion provided 95 with an upstanding rib flush with its outer edge.

In applying the strips to the roof each strip is laid between a pair of the batten strips, with the hooked portion of the strips 100 consecutively engaging the batten strips, whereby the outer ribbed portions 12 formed on the edges of the strips, opposite the hooked portions, may engage over the upstanding ribs 15 of the adjacent strips, in 105 the manner illustrated in Fig. 4. When in this position the portions 11 of the strips lie flat against the portions 16 of the adjacent strips, and the outer ribbed portions 12 snugly engage the upstanding ribs 16. 110

Previous to the engagement of the ribbed portions of the roofing plates, the flaps 16 are secured to the battens by anchor-pins 17, with their lengths disposed horizontally or 5 in a transverse direction relative to the length of said batten strips and plates, said anchor-pins or nails entering the batten strips from the sides thereof. When the flaps 16 have been nailed in position and the ribbed portions have been engaged, as shown in Fig. 4, said ribbed portions are then bent over 10 the top portions 14 of the hooks and hammered flat into the position shown in Fig. 2.

From the foregoing description it will be 15 seen that, owing to the fact that the anchor-pins or nails 17 are arranged horizontally, wind pressure under the sheathing plates tending to lift the same from the roof frame will be effectually resisted, which result is 20 not attainable wherein anchor-pins or nails are positioned vertically for securing sheathing-plates, which vertically positioned nails have heretofore been employed and, in practice, found lacking as a confining means for 25 the reason that any upward draw of the plates can readily strip said nails from their seats as the stripping strain occurs in a direction parallel to the length of the nail.

By this construction, it is evident that 30 the joints occurring along the longitudinal edges of the strips are exceedingly strong and at the same time simply made, and will withstand the weather, and prevent rain 35 from getting under the strips. It is also to be noted that there are no nails exposed which might corrode, and thus leave open-

ings in which water might enter. This concealment of the nails also adds materially to the attractiveness of a roof constructed according to the method described. 40

The roofing is made in long strips, and the adjacent transverse edges of any two strips are connected by the ordinary locking joints 18, illustrated in Fig. 3.

Although I have described the preferred 45 embodiment of my invention, I may desire to make such changes in the construction, combination and arrangement of parts as do not depart from the spirit of the invention and the scope of the appended claim. 50

I claim:

The combination of a roof structure having parallel batten strips rectangular in cross-section and sheathing plates fitted thereto, each sheathing plate being provided with one uninterrupted edge folded over the batten, horizontally disposed anchor-pins extending through the folded edge and vertical side walls of the batten, the length of the pins being transverse relative to lifting strain of the vertically disposed edges of 55 said plates induced by climatic conditions, the opposite edge of each plate being provided with an upturned uninterrupted fold 60 adapted to form an uninterrupted lapped seam union with the pin-secured edge of another plate, whereby the anchor-pins are sealed. 65
